DEVICE FOR FEEDING HIGH PRESSURE BOILERS

Hermann Hähnle, Giengen-on-the-Brenz,
GermanyApplication February 27, 1934, Serial No. 713,113
In Germany February 27, 1933

1 Claim. (Cl. 122—457)

This invention relates to a device for feeding high pressure boilers of the type described in my Patent #1,933,853 of November 7th, 1933. In this patent a device is described wherein the pump working against the pressure of the boiler is eliminated and is substituted by a feeding device which has the same pressure as that of the boiler. The feeding devices operate therefore as back feeders and their exhaust steam is utilized for the preliminary heating of the feeding water which is situated in hermetically closed heat exchangers. The water situated in these heat exchanging containers is kept under high pressure so that it can be heated to a high temperature, even close to the temperature of the boiler, without being transformed into steam.

As stated in the above mentioned patent the pressure of the exhaust steam of the feeding devices can be lowered before the steam is introduced into a heat exchanger, the pressure being preferably diminished in a power engine. The subject matter of the present invention is the further development of this feature and the application thereof to steam boilers connected with steam conduits supplying steam under different pressures. For example, the subject matter of the present invention can be applied to a system of conduits having steam of a comparatively low pressure which is supplied with steam from a machine which operates on the steam of a high pressure boiler or from boilers containing steam of a correspondingly low pressure.

It is known in prior art to introduce into a low pressure system the exhaust steam of other steam consuming units, said exhaust steam having substantially the same pressure as that of said system. However, devices of this type operate under entirely different circumstances. In my above mentioned patent containers for steam are described which operate intermittently and which contain steam having a very high original pressure. These containers cannot be employed as a source of steam which must be supplied continuously under a low pressure and cannot be easily combined with such devices.

An object of the present invention is the provision of a device by means of which steam situated in the containers described in my above mentioned patent can be continuously supplied to a conduit system containing steam under a comparatively low pressure.

The above and other objects of this invention may be realized through the provision of a device comprising a high pressure boiler which is combined with a consuming unit for the steam

having a corresponding original pressure. The device is further provided with a system of conduits containing steam of a low pressure, a feeding pump and at least two feeding devices which are connected in series with a hermetically closed heat exchanger; conduits connect the steam chamber of the boiler with the upper portion of the feeding devices. Conduits are also provided between the lower portion of the feeding device and the heat exchanger. The boiler is connected in series with the heat exchanger and the water chamber of the boiler is connected with said lower portion of the feeding devices. The conduits for the steam and water are provided with valves which intermittently switch the feeding devices on and off and connect them either with the steam chamber or with the water chamber of the boiler. When the feeding devices are empty this upper portion is connected with the heat exchanger or with the low pressure conduit system. As soon as the pressure of the exhausted steam drops to that of the pump the lower portion of the feeding device is connected with the pump so that the former is supplied with water.

The invention will appear more clearly from the following detailed description when taken in connection with the accompanying drawing showing a feeding device constructed in accordance with the principles of the present invention.

The diagram illustrates a high pressure boiler 1 and a steam engine or machine 2. A low pressure conduit system 3 is connected with the machine 2 by a system of pipes 4 provided with a valve 5 and is supplied with steam from the machine 2. The conduit system 3 which is adapted to contain steam under low pressure may also be supplied with said steam from boilers not shown in the drawing which are adapted to transmit steam of this low pressure to the conduit system 3. The boiler 1 is supplied with water in the same manner as that described in my above mentioned patent, namely, through two feeding devices 6 and 6'. The way in which the two feeding devices 6 intermittently supply water to the boiler 1 is fully described in my above mentioned patent. The feeding device 6 is connected by a pipe 8 provided with a valve 9 with the steam conduit 7 of the boiler while the feeding device 6' is connected with a conduit 7 by a pipe 8' having a valve 9'. The upper portion of the container 6 is connected with a pipe 11 which is provided with valves 10 and 10'. The pipe 11 leads to a heating coil 12' which is situated within a heat exchanging container

12. The container 6' is connected with a pipe 11 by a pipe 11' having valves 10'' and 10'''. Another pipe 14 forms a continuation of the pipe 11 and is provided with a valve 13. The pipe 11 leads to the low pressure conduit system 3. Similarly, the pipe 14' leading to the system 3 forms a continuation of the pipe 11' and has a valve 13'. The bottom of the container 6 is connected by a pipe 16 which is provided with a valve 15 10 with the bottom of the heat exchanger 12, while the top of the heat exchanger 12 is connected by a pipe 17 with the boiler 1. A pipe 16' having a valve 15' connects the container 6' with the pipe 16. A feeding pump is provided with a pipe 18 15 which carries a non-return valve 19 and which leads to the lower portion of the container 6. A pipe 18' having a non-return valve 19' connects the pipe 18 with the container 6'. The device operates as follows: After the feeding device 6 has completed its operation, the valves 9 and 15 are closed and the valves 10 and 10' opened. The exhaust steam of the container 6 flows through the heating coil 12' and the steam in the container 6 drops substantially to 20 the pressure of the conduit system 3. Then the valve 10' is closed and the valve 13 is opened. At the same time the valve 19 is operated as described and illustrated in my above mentioned patent so that the container 6 is again filled with 25 water which forces the steam remaining in the container 6 into the system 3. Then the valves 10, 13' and 19 are closed and the valves 9 and 15 are opened again, so that the water contained in the container 6 flows to the boiler or the 30 heat exchanger 12.

The same process is carried out with respect to the feeding device or container 6'. However, the container 6' transmits its water to the boiler 35

and the first portion of its steam to the heating coil 12' of the heat exchanger 12 while the container 6 is being filled with water; the container 6' gives up the last part of its steam to the lower pressure system 3 and is filled with 5 water while the container 6 transmits its steam to the heating coil 12'.

The valves are operated in the manner described in my above-mentioned patent.

I claim:

A device for feeding high-pressure boilers, comprising in combination with a high-pressure boiler, a feed pump and a low-pressure system; at least two feeding devices adapted to contain water and steam, a heat exchanger having a 15 heating coil and connected at one of its ends with the bottom of said boiler, conduits for steam having valves and connecting the steam chamber of the boiler with the upper portions of said feeding devices, conduits for water having valves 20 and connecting the lower portions of said feeding devices with the other end of said heat exchanger, conduits for steam having valves and connecting the upper portions of said feeding devices with said heating coil and said low-pressure system, and conduits having valves and connecting said feed pump with the lower portions of said feeding devices, whereby the feeding devices may be connected intermittently and 25 one after the other with the boiler, that feeding device which is filled with steam being first connected with said heating coil to reduce its steam pressure to that of the low-pressure system, and then connected with said low-pressure system and 30 said feed pump, whereupon this cycle of operation may be repeated.
